Application December 1, 1931, Serial No. 578,270

41 Claims. (Cl. 242—58)

This invention relates to a web roll replenishing device for printing machines and other machines to which a web is supplied, having for its principal object, the provision of an improved simplified method and means for securing the web of a fresh or replacement web roll to the web of an exhausting web roll without stopping or interruption of the operation of the machine while changing from one web roll to another.

10 Another object is to provide novel means for assuring the positive change from one web roll to another for the purpose of an uninterrupted or continuous web feed.

Another object is the provision of a device of 15 comparatively simple design and relatively inexpensive construction that may be quickly applied to conventional web roll support mechanism without change or reorganization thereof for replenishing the web of an exhausting roll by 20 the web of a fresh or replacement roll at high speed without interruption or retardation of the printing machine.

A further object is to provide a novel attachable device adapted to form a part of or to be 25 installed on printing presses for securing and severing tabs or other means for maintaining the end of the web or a fresh or replacement roll in juxtaposition against the body portion thereof until joined without interruption to the web of 30 an exhausting web roll.

It is also an object of the invention to provide means for securing the web end of a roll and separating same from the roll, when required, of 35 generally improved construction, whereby the device will be simple, durable and inexpensive in construction, as well as convenient, practical, serviceable and efficient in its use.

With the foregoing and other objects in view, which will appear as the description proceeds, 40 the invention resides in the combination and arrangement of parts, and in the details of construction hereinafter described and claimed, it being understood that various changes in the precise embodiment of the invention herein disclosed 45 may be made within the scope of what is claimed without departing from the spirit of the invention.

The preferred embodiment of the invention is 50 illustrated in the accompanying drawings, where-
in:

Figure 1 is a fragmentary end elevational view of a web handling mechanism to which a web roll replenishing device embodying our invention has been operatively attached, showing the relative 55 position of the parts, prior to the securing of the

web of the fresh roll to the web of the exhausting roll;

Figure 2 is a fragmentary elevational view looking in the direction of the arrow 2 of Figure 1;

Figure 3 is a perspective view of one form of 5 our invention operatively applied to a fresh or replacement web roll showing the position of the web retaining and severing member of my invention immediately before the severing of the straps or tabs, etc., holding the free end of the fresh roll;

Figure 4 is a view of the web roll shown in 10 Figure 3, immediately prior to the placing of the straps between the jaws of the web retaining and severing member shown in Figure 3;

Figure 5 is an enlarged fragmentary end elevational view showing the means employed for impinging the web of the exhausting roll to the 15 end of the fresh roll, before operation thereof;

Figure 6 is an enlarged fragmentary end elevational view of a form of our invention partly in 20 section, showing the web of the exhausting roll being pressed or pasted to the end of the fresh roll in a position where the cutting knife is just about to cut the strap which confines or binds the free end of the fresh or replacement roll to 25 the body portion, and the strap which maintains the web end retaining and releasing member B in operative position;

Figure 7 is a fragmentary end elevational view 30 of the invention immediately after the knife has cut both the web end-binding and member-supporting straps, and the web of the exhausting roll has been pasted to the free end of the fresh roll;

Figure 8 is a horizontal sectional view, as seen 35 from below, showing portions of the web roll with its supporting mechanism, viewed in the direction of the arrow 8 of Figure 6;

Figure 9 is a fragmentary elevational detail 40 view, partly in section, of the adjustable strap, adhesive paper tape, or tab securing members forming a part of our invention;

Figure 10 is a fragmentary perspective view of 45 a modified form of the invention operatively applied to the side margins of a web roll;

Figure 11 is an enlarged fragmentary perspective view of details shown in Figure 10;

Figure 12 is an enlarged elevational detail, with 50 parts broken away for clearer illustration, of another modified form of the invention;

Figure 13 is a fragmentary sectional view taken on line 13 of Figure 12, looking in the direction of the arrows; and

Figure 14 is a detail sectional view taken on line 55

14 of Figure 12, looking in the direction of the arrows.

In the drawings wherein similar characters of reference indicate corresponding parts in the several views of the preferred form of the invention, "A" designates a web roll handling and supplying device which as shown in Figure 1 includes a frame 16, suitably secured to a base or floor 17. The web roll supporting member or reel 18 as shown in Figure 1, has two web rolls supported thereon; i. e., a fresh or replacement web roll 19 and an exhausting web roll 21, it being understood that as customary the web reel support may be swung or rotated to bring the web rolls into desired positions for feeding, transfer, etc., as hereinafter described.

A web end retaining and releasing member "B" forming an important feature of the present invention, a pair of which are employed, one at each end of the fresh roll 19,—comprises an arm 22, composed of two pairs of sections or straps, 23, 24, as shown in Figure 3, slidably and adjustably joined in any suitable manner as by the slots 25, formed in sections 23, and the T-bolts 26, or other suitable fastening means which ride in the slots 25, and are threadedly engaged in the straps or sections 24, thereby serving to adjustably connect the sections 23, 24, one of which 24, is slid longitudinally relatively to the other in order to accommodate the member B to rolls of various diameters, when necessary or desired.

The section 23 is formed with or has secured thereto, a collar or annular member 27 which is rotatably mounted either directly on the core of the web roll which in this instance is the fresh roll 19, or on means hereinafter described which rotatably support the web roll. The other section of the arm 22 is formed with or has secured thereto a strip or tab holding and cutting instrumentality which comprises a jaw-shaped head or end 29 having an opening 31, which receives straps or tabs and the like, hereinafter described, which may have an adhesive on one or both sides or the top and bottom surface. Two straps 32, 33, preferably of paper or other suitable strip material, are preferably placed in helical relation on the roll 19 as shown by way of illustration in Figures 3 and 4 and hereinafter more fully explained. A knife or cutting element 34 is hinged or pivoted on a pin 35, secured in the end or head 29 and swings or rocks in a pair of similarly positioned slots 36, 37, formed in the upper and lower jaws 38, 39 respectively of the head 29. The knife 34 is maintained in normal raised position in the upper jaw 38 by a spring, hereinafter described, thus leaving the opening 31 between the jaws 38, 39 free for receiving the strap or tab 32, 33 and the other tab hereinafter mentioned. It will be observed the head of the knife 34 is provided with a widened or flattened portion 41, the underneath side of which, acts as stop for the said knife when it abuts against the top of the upper jaw 38 after it has accomplished its functions by severing the straps or tabs 32, 33, while the top of the flattened portion acts as anvil or seat which may strike against abutments or marginal projections 42, formed or secured to the brackets or plates hereinafter referred to, forming a part of the web-joining or splicing member hereinafter described more fully.

The web-joining or splicing member comprises a pair of arms 44, 45, keyed or fastened in opposed relation to the shaft 46 which is rotatably supported in bearing hangers 47, suitably secured to the frame 16. To each of the arms 44, 45, a

slotted plate 48, having bent flanges 49, to which the brush assemblies 51 are fastened, is adjustably secured by screw bolts 52 which ride in the slots 53 formed in the said plate 48.

As best shown in Figures 6 and 7, the head 29 of each of the web retaining and severing members at the opposite ends of the replacement roll 19 is provided with an internal spring 54 mentioned above, which is connected at one end to an inwardly projecting portion of the knife 34, and at the other end to an internal part of the head 29. The spring 54 serves to maintain the knife 34 in normal raised or inoperative position, leaving the opening 31 of the head 29 free to receive the straps or tabs 32, 33 preparatory to their severance by the knife 34, as clearly shown in Figure 6.

In Figure 7, the upper or flattened portion 41 of the head of the knife 34 is engaged with the abutments or projecting plates 42 and has been pressed downwardly through the opening 31 to the position shown within the slotted lower jaw of the head 29, thus severing the straps 32, 33.

By further inspection of Figures 6 and 7, it will be seen means for securing the pair of helically positioned straps or tabs 32, 33, mentioned above, and an additional pair of straps 55, 56, which are also helically positioned on the body portion of the roll 19 and in crossing or angular relation to the first mentioned pair of straps 32, 33,—are provided in the head 29,—the means comprising a pair of small rollers 57, having a knurled surface and reduced ends or axles 58, which are received in slots 59, formed in a portion of one of the side walls or surfaces of the head 29 which is formed or provided with a pair of shelving recesses or pockets 61 in which the said rollers 57 are secured by the engagement of the reduced ends 58 of the rollers 57 in the slots 59, above-mentioned. When the end portions of the tabs or straps 32, 33, and 55, 56 are passed under the knurled surface of the rollers 58, the sliding of the said rollers in the direction of the jaws 38, 39 of the head 29 will clampingly confine the straps as the rollers advance on the inclined or shelving surface 62 of the recesses 61.

The shaft 46 on which the arms 44, 45 of the web-splicing member 43 alluded to above are fastened, has secured thereto, an operating lever 63, having a pawl 60 which coacts with a ratchet segment 64 fastened to one of the bearing hangers 47, the lever 63 providing means for manually operating the web-splicing member 43, when desired, and for moving it out of the path of the rolls when the roll support is rotated.

In order to bring the web of the replacement roll 19 to the same speed as the web of the nearly exhausted roll 21, a feeding belt 65, mounted on a pair of rollers 66, 67, secured on shaft 68, 69 mounted in a frame member 71, is provided. The shaft 69, it will be noted, has a gear 72 fastened thereon, the gear 72 being engaged by a gear 73, secured to a vertically positioned shaft 74, rotatably mounted in the frame 16 and preferably having an operative connection with the driving system of the printing machine, so that the belt 65 travels at substantially the same speed as the traveling web W of the exhausting web 21. To the frame member 71, an arm 75, which engages an abutment 76 on the frame 16, is secured for the purpose of limiting the downward movement of the feeding belt, 65.

The operation of the device has been in part indicated from the foregoing details, but it will

be more fully understood from the following description.

On the free end of the replacement roll 19 which, as viewed in Figures 3 and 4, discloses a 5 pair of intersecting or meeting helixes and which preferably is torn, notched, cut, or a portion removed therefrom to provide a more or less V-shaped edge having the side marginal portions or tapering "fish-tail" ends 30, a pair of the binder 10 ribbons or tabs 31, 33, referred to above, is pasted, it being observed that the said ribbons or tabs, after pasting, will be positioned in helical 15 relation to the body portion of the replacement roll, and along the edge in substantial alignment therewith. The notching, tearing, or removing a portion from the free end of the replacement roll is most conveniently and expeditiously done by first applying or pasting the straps or tabs to the free end, the straps then serving as guides to 20 tear out the portion of the free end alluded to. The said straps further provide a reinforcing means for the end of the web to prevent said web end from tearing when the roll is rotated preliminary to making a web join.

25 The outer surface of the helically positioned straps 32, 33, is next smeared with a suitable adhesive, care being taken to prevent any adhesive getting on the body portion of the replacement roll, while the ends of the same straps overlapping 30 the opposite ends or sides of the fresh roll 19, are clampingly secured in the upper of the pockets 61 of each member B at the opposite ends of the fresh roll 19, by engaging the said ends under the knurled rollers 57 and thrusting 35 the latter towards the jaws 38, 39 until the said overlapping ends are gripped between the knurled surface of the rollers and the adjacent shelving surface 62 of each of the pockets or recesses 61. The other pair of helically positioned 40 straps or tabs 55, 56, which are arranged in crossing or angular relation to said first-mentioned pair of straps 32, 33 are pasted on the body portion of the fresh web roll 19 with their ends also secured under the knurled rollers 57 in 45 the lower of the pockets 61 of each member B, it being observed that the last-mentioned pair of straps 55, 56, serve mainly to sustain the web retaining and releasing member B in the operative 50 position shown in Figure 3 preparatory to cutting both pairs of tabs 32, 33, and 55, 56, thus releasing the web of the replacement roll as herein-after described; while the lower pair of straps 32, 33 serve principally to confine or bind temporarily 55 the V-shaped edge of the fresh web roll to the body portion thereof while the latter is rotating in the direction indicated by the arrow, until the moment predetermined for the joining or splicing of the web of the replacement roll to the traveling web W of the exhausting roll after the peripheral speeds of both webs have been equalized.

60 Assuming the lower web roll 21 to have been unwound or used to the amount indicated in Figure 1, the web reel support 18 will be swung or rotated to bring the fresh or replacement roll 19 to the position shown in the last mentioned figure. The feeding belt 65 will now be lowered to operative engagement with the periphery of the replacement roll 19, and the latter rotated until the peripheral speed of same is equal to that of the traveling web W of the now nearly exhausted 65 lower roll 21.

70 It will now be seen that as the replacement roll rotates, with its free end bound to the body portion by the lower pair of tabs 32, 33, the pair of members B of our invention, at the opposite

ends of the fresh roll 19, sustained by the upper tabs 55, 56, will rotate therewith until approximately the moment when the peripheral speeds of the webs of both rolls are approximately equal, whereupon the lever 63 is manipulated to turn the shaft 46 to swing the brush assemblies 51 against the traveling web W of the exhausting roll 21, thereby impinging the latter against the adhesive-smeared outer surface of the helically positioned pair of straps 32, 33 which are pasted 10 on their inner surface to the fish-tail edge or end of the web of the replacement roll 19. Almost simultaneously with the engagement of the brush assemblies 51 with the web W for applying same to the sticky outer surface of the straps 15 or tape 32, the flattened head 41 of each knife or cutting element 34, will strike against the abutments 42 of the web splicing member 43, which may have shock-absorbing material secured thereto, thereby causing the said knife 34 to pass 20 downwardly through the openings 31 and thus cutting both upper and lower straps or tabs 32, 33, and consequently causing the pair of web-retaining and releasing members B to completely release the end of the web of the replacement roll 25 19, now pasted to the web W of the exhausting roll, so that the web of the replacement roll may serve without the slightest impedance as a continuation of the web of the exhausted roll without delaying the operation of the press in the 30 slightest degree. Both of the web retaining and releasing members B, which are freely rotatable on the core engaging means of the fresh roll or the means supporting same alluded to above, will now drop to inoperative or depending position, the web of the exhausting roll meanwhile 35 having been severed by any convenient means.

This completes the cycle of a change from one roll to another without stopping or retardation, which may be repeated as many times as desired, 40 or until the run has been completed. The invention is particularly designed and adapted to be operatively applied to practically all types of machines employing web roll-handling mechanism, since the application of the tabs and adhesive and the securing of the tabs to the permanently mounted pair of members B require only a few moments. While the extremities of the "fish-tail" ends 30 on either side of the marginal sides of the free end of the replacement web roll 50 19 are shown as arranged in substantially the same relative position at each end of the web roll 19 and in helical relation to the body portion thereof. It is to be noted that one of the said "fish-tail" ends 30 may be much shorter than the 55 other or leading fish-tail end, and it will be apparent that if desired, the end of the web may be cut on a long diagonal in which case, only one of the members B will be required, since one fork or portion of the "fish-tail" end alluded to above 60 would be eliminated.

The helical arrangement of the tab or tabs and the like on the free end of the roll and on the sides or margins of the body portion thereof in the forms shown, and the tearing or cutting or otherwise removing a portion of the said free end of the replacement roll 19 to form the "fish-tail" or helically positioned ends 30, in the manner indicated above, are also features of the present invention since they achieve by the utmost simplicity of means a highly efficient way of confining the free end of the roll to the body portion while the said roll is rotating, it being observed that the said "fish-tail" ends which are 75

forwardly directed or leading on the replacement roll 19 while rotating in the counter-clockwise direction indicated by the arrows in Figures 1, 3, etc., when secured by the above-mentioned tabs 5 or straps, will directly tend to exert a forward pull or drag and thus bind or confine the free end of the roll, while rotating, to the body portion. As pointed out above, the tearing of the free end of the replacement roll is accomplished 10 with certainty and dispatch by preferably first pasting the strip material or tabs in helical fashion on the free end, and then simply tearing out the portion of material from the V-shaped space between the said helically positioned straps, 15 using the tabs or straps as guides for this purpose.

It is to be noted that by pasting the strip material or tabs in helical fashion to the body portion of the roll, instead of parallel to the axis 20 or longitudinally of the roll, distinctly serves to prevent air from getting under the free end portion of the web, while the roll is rotating, and likewise the tearing or otherwise removing material from the free end of the web which is 25 conveniently done by using the tabs as guides for the tearing to provide the "fish-tail" or equivalent portions is particularly adapted to prevent air from getting under the free end of the web of the replacement roll during rotation.

30 In Figure 8, we have illustrated suitable roll chuck mechanism for rotatably supporting web rolls in a web roll or reel support, to which mechanism the invention can be quickly attached. The chuck mechanism here illustrated 35 provides means for quick and fine axial adjustments of the members which engage the web roll cores so that the rolls may be loaded into the support expeditiously.

By inspection of Figure 8, it will be noted the 40 section 23 of the strap or arm 22 of the web retaining and releasing member B of the invention is bolted or otherwise suitably fastened to the rotatably mounted annular member or collar 27, forming a part of the chuck mechanism herein 45 mentioned. The supporting arm 78 of the present chuck mechanism is provided with a sliding sleeve 79, having a hand wheel 80, providing for a quick axial or lateral adjustment of the sleeve 79 and the parts connected thereto. A block 50 81, slidably keyed to and concentrically positioned within the sleeve has a cone-shaped head 82, which enters the core 83 of the web roll 19. The comparatively quick axial or lateral adjustment of the sleeve 79 and the block is effected by an 55 arcuate groove 85 in the sleeve 79 and a pin 86 in a hub 87, forming a part of the supporting arm 78, it being understood that the rotation of the hand wheel 80 will move the sleeve when turning, in an axial direction by the coaction of the fixed 60 pin in the arcuate groove 85.

The fine adjustment is accomplished as follows: The block 81, on which the collar or annular member 27 is rotatably mounted, has a pocket 88 which receives one of the threaded 65 ends of a left and right hand screw 89, having a reduced portion 91 receiving a thrust collar 92 which is fastened to the block 81. The outer portion of the screw 89 is threadedly engaged in the hub 93 of a hand wheel 94, employed for 70 making fine adjustments, the hub 93, having an annular recess or groove 95 in which a second thrust collar 96, secured by screw 97 to the hand wheel 80, is engaged.

In operation, it will be observed that when the 75 smaller hand wheel 94 is rotated for fine ad-

justment, the fixed screw 89 threadedly engaged in and coacting with the hub 93 of the hand wheel 94, will further thrust the block 81 carrying the rotatable cone-shaped head 82 into the core 83 of the web roll 19, after the coarse or quick adjustment effected by the larger hand wheel 80.

The chuck mechanism herein described and shown in Figure 8, forms no part of the present invention since any conventional type of mechanism for rotatably supporting web rolls may be employed, but has been found to be a convenient means of supporting web rolls in web reel supports of the general character herein indicated. The parts of the chuck mechanism illustrated 15 in fragmentary section at the right hand side of the web core 83 shown in Figure 8, are assumed to be non-adjustable or in fixed position with the exception of the rotatable cone-shaped head 82, while nearly all of the parts of the chuck 20 mechanism at the left hand side of the same core 83 are movable or adjustable as indicated, so that the fresh and exhausted web roll can be moved into and out of position as required, from one side alone of the web reel support. 25

In Figures 10 and 11, we have shown a modified form of the invention which requires the use of only one comparatively short strap or tab at each end of the fresh web roll 19 instead of two as in the form shown in Figures 1 to 9 30 inclusive. In the present instance, the web releasing and retaining member C of the form shown which also serves as an anchorage for the strip material or tabs differs from the member B in that the jaw-shaped head 98 of the instant 35 form has an offset or laterally projecting portion or ledge 99, the top surface of which, as at 101 is substantially flush with the lower jaw 102 of the head 98. A portion of the single binder ribbon or tab 103 here employed, after one end 40 thereof has been pasted on its under surface to the body portion of the roll 19, preferably in helical relation thereto, as shown in Figure 11, is passed over the said top surface 101, thence downwardly and around the lower projecting 45 portion 104 of the said ledge 99 and thence obliquely or angularly upward as at 105 over the top of that portion of itself which rests on the top of the ledge 99, continuing in a diagonally crossing direction over an adjacent edge of the 50 free end of the fresh web roll 19 to which it is pasted on its inner surface. While the sequence just described is preferable, since the portion of the binder strip 103 adhering to the free end is uppermost and consequently free after severance 55 by the knife 106 to be carried away with the traveling web of the replacement roll after being glued thereto, it will be understood that, if desired, the said strip 103 may first be pasted to the free end of the replacement roll, then passed 60 over those portions of the jaw-shaped head 98 over those portions of the jaw-shaped head 98 65 enumerated above, then passed over the portion of the strip sticking to the free end, and finally pasted to the body portion of the replacement web roll. In the last recited sequence, the placing of that portion of the strip material immediately adhering to the free end of the web underneath the portion of the strip glued to the body portion would not be as advantageous as the 70 preferable arrangement since there would be a temporary overhanging or superincumbent portion of strip material that would be thrust aside as the free end of the replacement web became attached to and moved with the traveling web of the exhausting web roll.

The preferred sequence in this modified form of the invention, it will be noted, is the reverse of the preferred sequence employed in the form of the invention, best shown in Figures 1 to 4 inclusive, wherein the free end of the replacement roll is notched by first pasting the straps 32, 33 thereon and then a portion of the free web end torn out while using the said straps as guides. The second pair of straps 55, 56 are subsequently pasted on to the body portion of the replacement roll and may be used at once to support the member B either before or after the smearing of the outer surface of the first-mentioned pair of straps 32, 33 with adhesive. The knife 106 of the member C performs practically the same functions as in the form shown in Figures 1 to 9 inclusive. In this form, however, the folded over or crossing portions of the single strap or tape 103 at each end of the web roll 19, are simultaneously cut as the knife 106 of each of the pair of members C employed, one at each end of the roll 19, engages the abutment or trigger projections mentioned above.

In Figures 12, 13 and 14, a modified form of the invention is shown which employs one strip of adhesive tape or strap, and etc., 106, which may be perforated or creased as at 107 to facilitate tearing or severance thereof, is pasted to the free end of the web roll 19, in helical relation to the body portion thereof, one end or portion of the tape 106 being in a strap or tape and the like securing member 108 which is similar in some respects to the strap or tab securing member, best shown in Figures 6, 7 and 9. The member 108 includes a frame or shell 109, having a shelving pocket or recess 111, in which a tape or ribbon engaging roller 112, having a knurled surface is arranged. The knurled roller 112 has reduced ends 113, which are slidably received in elongated slots 114, formed in the shell 109, thus permitting the roller to be slid in the pocket 111 for the purpose of clampingly engaging the tape 106 confined against the shelving surface of the said pocket 111 and the adjacent knurled surface of the roller 112 in the manner described above in connection with the details shown in Figures 6, 7 and 9. A portion of the shell or frame 109 has flanges as at 115 which are received in grooves 116, formed in an annular member 117 for a purpose which will appear hereinafter, while a rack 118 is provided on one end or edge of the shell 109. The rack 118 is engaged by a pinion 119 rotatably mounted on a stud or pin 121, the pin 121 being secured to the annular member 117, the pinion 119 meshing with a rack segment 122, formed on an arcuate strap 123, which is fastened to an annular portion 124 formed with or secured to an arm or trigger member 125, which coacts with a pin or stop 126, secured to an arm 127, or a part of the adjacent web splicing member or frame. The arm 125 is held in the normal position shown against a stop pin 128, and is secured to the annular member 117 by a spring 129, fastened at one end thereto, the other end of the spring being attached to a cam-shaped member or latch 131, having a slot 132, in which rides a pin 133, secured to a forked extension or projection 134, of the shell 109. The annular member 117, as indicated in Figure 12 by the dotted line at the lower portion thereof, may have a counter-balancing weight 130, if desired. The cam-shaped member or latch 131 is provided with a pin 135, fastened thereto, to which is secured one of the looped ends 136, respectively of a clutch member or band 137, frictionally engaged with

the hub 138 of the cone-shaped head 139 of the web core engaging member 141, shown in fragmentary section in Figure 13. The other looped end 142 of the clutch member or band 137 is fastened on a pin 143 on the annular member 117, serving as a pin or fulcrum for the cam-shaped member or latch 131, the pin 143 traveling in an arcuate slot 144, formed in the annular portion 124 of the arm 125, for a purpose hereinafter described.

The functions and manner of operation of the modified form of the invention shown in Figures 12, 13 and 14 has been in part indicated by the foregoing details, but will be more fully understood from the following description:

Assuming as best shown in Figure 12, the fresh or replacement web roll 19 has been operatively mounted on the member 141 with its free end notched or torn to provide the helically positioned portions engaged by the adhesive tape 106, a portion of which latter is clampingly held in the tape securing member 108; and that the said fresh roll and the core-engaging member are revolving at normal press operating speed, and also assuming the clutch 137 to be as illustrated, in frictional engagement with the hub 138, and the trigger arm 125 to have struck against the stop 126, it will be noted that further rotation in a counter-clockwise direction of the assembly shown in Figure 12 will first cause the immediate severance or breaking of the helically arranged adhesive paper tape 106 at the point of the perforations 107, thus completely liberating the free end of the fresh roll 19 at the time when the traveling web of the exhausted roll is being or has been applied to the sticky upper surface of the said tape in order to bind or splice same, and consequently the web of the fresh roll, to the web of the exhausted roll, in the manner described above in connection with Figures 1 to 9 inclusive.

It is to be noted that the momentum of the annular member 117 will carry it ahead after the arm 125 has engaged the stop 126, and it will carry the pin 133 on the forked extension 134 to the end of slot 132 thus moving the latch 131 about its pivot 143 on the annular member 117, thereby loosening the band of the clutch 137 and freeing the annular member from the hub 138. The annular member 117 then turns forward with respect to the trigger arm 125 which is held stationary, thereby turning the pinion 119, hitherto motionless on its axis, with respect to the rack 118 and rack segment 122, and consequently causing the shell 109 and its attached rack 118 to move in the groove or slides 116. The movement of the tape securing member 108 along the grooves 116 will, as mentioned above, first cause the immediate severance or breakage of the adhesive paper tape 106 at the point of the perforations 107, thus completely liberating the free end of the roll 19 from the body portion of the roll in order to permit the unimpeded attachment of the free end of the roll to the traveling web.

The separation of the looped ends 136 and 142 will free the clutch band 137 from frictional engagement with the hub 138 of the web-core engaging member 141, and as a consequence will permit the hub 138 to turn freely relatively to the clutch assembly and the parts connected thereto. It will be noted that when the clutch band 137 is released after the pin 133 on the moving tape-engaging member 108 has travelled in the slot 132 sufficiently to engage the end of same and move the latch 131 about as pivot pin 143 enough to open the clutch band 137; the force exerted by

the tension spring 129 in tending to return the latch 131 to the position shown in Figure 12 will be counter-balanced by the available torque of the revolving hub communicated through the now 5 slipping clutch band 137 on the said hub. This will produce at the time now indicated, a condition of equilibrium between the clutch and the tension spring 129 resulting in an idling of the device until removed or engaged with another 10 fresh roll.

We are aware that the invention may be embodied in other specific forms without departing from the spirit or essential attributes thereof, and we therefore desire the present embodiment to 15 be considered in all respects as illustrative and not restrictive, reference being had to the appended claims rather than to the foregoing description to indicate the scope of the invention.

What we claim is:

20 1. Means for confining the free end of a web roll to the body portion thereof while rotating which comprises strip material pasted adjacent an edge of said free end so as to overlap an end of the body portion and anchored at said end to a member rotated with said web roll.

25 2. Means for confining the free end of a web roll to the body portion thereof while rotating, said free end having an edge diagonally extending with respect to the body portion, which comprises strip material helically positioned with respect to the body portion and arranged along the said diagonally extending edge and anchored adjacent an end of the body portion of the roll to a member rotated with said web roll.

30 3. Means for confining the free end of a web roll to the body portion thereof while rotating which comprises strip material helically positioned with respect to the body portion and arranged on either side of a notch formed in the said free end, said strip material being anchored adjacent an end of the body portion of the web roll to a member rotated with said web roll.

35 4. A web end securing means for a replenishing web roll for a web printing machine, including, a strap on the end of the web, helically positioned with respect to the periphery of the roll and projecting beyond one end of the roll, and an anchorage at the end of the roll to which the strap may be secured, said anchorage including means arranged adjacent said web roll and engageable with said strap.

40 5. A web end-securing and releasing means for a replenishing web roll for a web printing machine, including, a strap on the end of the roll helically positioned with respect to the periphery of the roll and projecting beyond one end of the roll, an anchorage at the end of the roll to which the strap may be secured, and means for severing the strap.

45 6. A web end-securing and releasing means for a replenishing web roll for a web printing machine, including, a strap on the end of the roll helically positioned with respect to the periphery of the roll and projecting beyond one end of the roll, an anchorage at the end of the roll to which the strap may be secured, and means on the anchorage for severing the strap.

50 7. As an article of manufacture for use with web roll changing mechanism, an abutment secured to said mechanism, a member provided with tape securing and severing means, said means being attachable to tape secured on a rotating web roll adapted to be mounted on said mechanism for confining a free end of the rotating web 55 roll to the body portion thereof, said means being

operated by engagement with the abutment on the mechanism to sever the tape at a predetermined time.

8. In a web roll replenishing device of the character described, a member having an opening to receive web end-confining strip material, said member being rotated with said web roll and instrumentalities secured to the member for gripping said material and cutting same when required to liberate a free end of a web roll for 10 splicing to a traveling web of another roll.

9. In combination with the free end of the body portion of a web roll adapted to be revolvably mounted on a web roll support, said free end having a diagonally-extending edge, strip material 15 pasted on the free end adjacent the said edge, said material having portions overlapping ends of said web roll, an instrumentality rotatable with said web roll and means rotatable with said web roll for temporarily fastening the overlapping 20 portions of the strip material, until separated therefrom when engaged by the said instrumentality.

10. Means for confining the free end of a web roll to the body portion thereof while rotating, 25 and liberating the said free end at a predetermined time for splicing to a traveling web of another web roll, which comprises strip material pasted along an edge of said free end, an anchorage mounted adjacent an end of said body portion for rotation with same, said strip material being fastened to the anchorage, said anchorage having means for separating said strip material from said last mentioned end at a predetermined moment.

11. In a web replenishing device, a tab on the end of the web of a web roll and projecting beyond the end of the roll, an adhesive on the outer surface of the web adjacent the end thereof, means for securing the tab to prevent unwinding 40 of the web, means for effecting contact of the said adhesive with a running web, and means for severing the tab.

12. In combination with the free end of a web roll adapted to be revolvably mounted on a web 45 roll support, said free end being provided with a single notch, strip material helically positioned with respect to the body portion pasted on the free end, an instrumentality rotatable with the web roll, and means rotatable with the web roll 50 and arranged adjacent an end of the web roll for temporarily fastening the strip material but releasing same at a predetermined time when engaged by the instrumentality.

13. Means for splicing the web of a replacement web roll to the traveling web of an exhausting roll during the operation of a coating printing machine at comparatively high speed which comprises in combination a strip of material pasted on a free end of the web of the replacement roll, said strip of material being perforated at one portion, a revolvable axial support on which said replacement web roll is mountable, an assembly secured on said axial support, said strip of material being fastened to said assembly, 65 and instrumentalities connected to said printing machine and engageable with said assembly for actuating same to sever the strip of material when the replacement web has been spliced to the traveling web.

14. A method of substituting a web from a replacement web roll for a web running to a machine from an exhausting web roll, including, applying separate adhesive smeared straps on the free body portion and end of the replacement 75

- roll, and leaving a portion of each strap extend beyond the roll ends, gripping said extended ends, rotating the replacement roll at a peripheral speed substantially equal to the speed of the web 5 running from the exhausting roll, effecting contact of the running web with the surface of the replacement roll, and cutting the extended strap ends as the adhesive smeared straps meet the running web, thereby freeing the end of web of the replacement roll so that same may be operatively joined to the web of the exhausting web roll.
15. A method of substituting a web running to a printing machine from an exhausting web roll with a web from a replacement web roll which consists in applying separate pieces of strip material having adhesive thereon to a free end and a body portion of said replacement roll and leaving a portion of each strap extend beyond the roll ends, gripping said extended ends, then rotating the replacement roll at a peripheral speed substantially equal to the speed of the running web, effecting contact of the strip material with the running web, and then severing the extended ends of said strips to liberate said free end from the body portion of the replacement web roll as the running web of the exhausting web roll adheres to same.
20. The method of substituting a web running to a machine from an exhausting web roll with a running web from a replacement roll which consists in applying separate pieces of strip material having adhesive material on the top and bottom surface thereof to a body portion and a notched free end of the replacement roll, and leaving a portion of each strip extend beyond the roll ends, gripping said extended ends, then rotating the replacement roll at a peripheral speed substantially equal to the speed of the running web, then contacting said running web with the upper surface of the strip material, and then severing the extended ends of said strip material to liberate the said free end as the running web adheres to the web of the replacement roll.
25. The method of substituting a web from a replacement web roll for a web running to a machine from an exhausting web roll, including, applying adhesive on the surface of the replacement roll adjacent to the end of its web, attaching a strap to the end of the web so the said strap projects beyond one end of the roll, securing the strap to means rotating with the roll, rotating the replacement roll at a peripheral speed substantially equal to the speed of the web running from the exhausting roll, effecting contact of the running web with the adhesive and severing the strap.
30. A method of confining the free end of the body portion of a web roll so as to bind same to the body portion while rotating, which consists in pasting strip material on said free end in helical relation to the periphery of the body portion with portions of said strip material overlapping an adjacent end of said web roll, then using said strip material as a guide for tearing material out of said free end to form a notch bordered by the strip material, and then anchoring the overlapping portions to said adjacent end.
35. The method of confining the free end of a replacement web roll to the body portion thereof preparatory to splicing same while rotating to a traveling web of another web roll, which consists in pasting strip material on said body portion and free end, then notching the said free end while the replacement roll is non-rotating, so as to provide two portions on the free end forwardly directed with respect to the body portion of the replacement web roll when rotating, and then fastening end portions of said strip material adjacent side margins of the body portion.
40. The method of confining the free end of the body portion of a replacement web roll preparatory to splicing same while rotating to a traveling web of another web roll which consists in pasting strip material on the said free end and in helical relation to the body portion, while the replacement roll is non-rotating, then tearing said free end to remove material therefrom for forming an edge helically extending with respect to the body portions, then securing the strip material adjacent an end of the body portion of the replacement roll.
45. The method of substituting a web running to a machine from an exhausting roll with a web from a replacement roll, which consists in notching a free end of the replacement roll to provide portions in helical relation to the replacement roll after applying strip material having adhesive thereon to said portions of the free end to serve as a guide for the said notching and for securing the free end, securing ends of the strip material to ends of the replacement roll, then rotating the replacement roll at a peripheral speed equal to the speed of the running web, effecting contact of the strip material with the running web, and severing the strip material to liberate said free end of the replacement roll as the running web adheres to the strip material secured to the free end.
50. The method of confining the free end of the body portion of a replacement roll preparatory to splicing same while rotating to a traveling web of another roll which consists in notching the said free end to provide an edge having two portions extending helically with respect to the said body portion, then pasting strip material on and in helical relation to the body portion of the replacement web roll and with end portions overlapping an end of the replacement roll, and then fastening a part of said strip material on said notched free end and then securing a portion of the said strip material adjacent side margins of the body portion.
55. The method of confining the free end of the body portion of a web roll to the body portion while the web roll is rotating, which consists in pasting strip material on said free end and in helical relation to the body portion, with portions of said strip material overlapping an end of said body portion, then using said strip material as a guide for removing material from the free end, and then anchoring the overlapping portions of the strip material to a means rotatable with the web roll.
60. In web roll handling mechanism, in combination, means for operatively joining a traveling web of a revolving web roll to a web of another revolving web roll, an axial support for said revolving web roll, a member attachable to and freely rotatable about said axial support of said last mentioned web roll, means forming a part of said mechanism and coactable with said member for the joining of both of said webs while moving, and sheet material connecting the member to the last mentioned web roll for synchronous rotation therewith, said sheet material being severed by the member in time for the joining of both of said webs while moving at high speed by said means.
65. An assembly frictionally and operatively engageable with a rotating support forming a

- part of a printing machine, said support being adapted to have a web roll rotatably mounted thereon, a second web roll rotatably mounted on said support, said second web roll having a web traveling to the printing machine, the first-mentioned web roll having a free end provided with adhesive means, a tape adhering to said free end and having tabs extending beyond each end of the roll, clamping means engaging said tabs and forming a part of said assembly, said assembly having means for automatically freeing itself from operative engagement with the said support to cause a strain upon and tear said tabs, and means for splicing said free end to said traveling web at a predetermined time.
26. In combination with a web roll rotatably mounted on an axial member carried by a support, strip material secured to a free end of a web roll for binding same to a body portion thereof, and adjustable mechanical means rotatable on the axial member, said mechanical means having an instrumentality for engaging said strip material to hold same to bind the said free end while the web roll is rotating, and another instrumentality secured to the mechanical means for cutting the strip material in time for the operative splicing of same to a traveling web forming a part of another web roll mounted on said support, said splicing being effected by manually operable means connectable to and coacting with said last-mentioned instrumentality.
27. In a web replenishing device, in combination, a member engaging tabs confining a free web end of a web roll to a body portion thereof, said web roll being adapted to be revolvably mounted on a support, said member, while frictionally rotating with said web roll, being carried by the said support, and means secured to the member for automatically severing the tabs and releasing the member from frictional engagement with the support in time to splice the said free end of the first-mentioned web roll to a traveling web forming a part of another web roll mounted on the same support, said splicing being effected by manually operable means connectable to said support and coacting with said member.
28. In a web roll replenishing device of the kind described, means for gripping straps confining a free end of a web roll to the body portion thereof, said straps supporting said means in a position adjacent a body portion of the web roll, said means comprising rollers slidably adjustable in a slotted member receiving the straps, said rollers coacting with a shelving surface formed in the slotted member for clampingly engaging said straps.
29. In combination with web roll handling mechanism including a web roll support adapted to rotatably receive a plurality of web rolls mountable thereon, a member attachable to and freely rotatable on the said support, and paper means for operatively supporting the member until a web of one of said rolls has been spliced to a web of another of the rolls while traveling, said paper means being rendered inoperative by said member approximately at the time the said webs are spliced, and manually operable means secured to said mechanism to effect the splicing of the webs.
30. Means for securing and severing tabs and the like pasted to a free end of a web roll mounted on a rotatable support, said means comprising an adjustable member freely rotatable on the support, said member having an opening receiving said tabs, clamping means slidably mounted in the member for gripping said tabs, and a severing instrumentality secured to the member and swingable into the opening for severing the tabs when positioned in the opening.
31. Means for securing and severing tabs and the like pasted to the free end of a web roll mounted on a rotatable support, said means comprising an adjustable member freely rotatable on the support, said member having an opening, a plurality of rollers slidably mounted on the member and coacting with a shelving recess formed therein for clampingly engaging portions of tabs received in the recess, and a cutting instrumentality rockably mounted on the member and movable through the opening for severing the tabs.
32. The method of confining the free end of the web of a web roll to the body portion thereof while rotating, which consists in arranging a tab in helical fashion on the free end of a web roll so as to provide portions overlapping side margins of the web roll and exert a forward pull on the said free end tending to confine the said free end to the body portion, and then securing said overlapping portions by means arranged at the end of said web rolls.
33. In combination with a printing machine, means for securing and severing tabs and the like pasted to a free end of a web roll mounted on a rotatable support forming a part of said machine, said means comprising an arm operatively connected by a clutch and coacting parts to a member rotatable on said support, said member having tab-securing and severing means operatively connected to the arm and clutch, whereby when said arm is arrested by engagement with a part of said machine while said web roll is revolving, said clutch will be disconnected.
34. In a web roll changing mechanism, a support for an expiring web roll and a replacement web roll, means for holding the end of the web of the replacement roll to the body portion thereof, including a clamping device for said means rotatable with the roll, and means cooperating with the clamping device to release the web end from the body of the replacement roll when the web of the running roll is joined with the end of the web of the replacement roll.
35. In a web roll changing mechanism, a support for an expiring web roll and a replacement web roll, the free end of the web of said replacement web roll being of fish-tail formation, means for holding the end of the web of the replacement roll to the body portion thereof, including a clamping device for said means rotatable with the roll, and means cooperating with the clamping device to release the web end from the body of the replacement roll when the web of the running roll is joined with the end of the web of the replacement roll.
36. In a web roll changing mechanism, a support for an expiring web roll and a replacement web roll, the free end of the said web of the replacement roll being of fish-tail formation, tape members having an adhesive thereon engaging the fish-tail edge, clamping devices for said tape members rotatable with the roll and adapted to hold the end of the web of the replacement roll to the body portion thereof, and means cooperating with the clamping devices to release the web end from the body of the replacement roll when the web of the running roll is joined with the end of the web of the replacement roll.
37. The method of replacing a running web from an expiring web roll with a web from a replacement roll, consisting of severing the free end of the web of the replacement roll on a

diagonal line, thereby forming a point adjacent an end of the said replacement roll, applying adhesive to the said free end, holding the said point against the body of the roll by a holding means rotatable with the roll, rotating the replacement roll at substantially the speed of the running web, pressing the running web against the replacement roll, and releasing the holding means from the point and from the roll when the running web engages the said point.

38. The method of replacing a running web from an expiring web roll with a web from a replacement roll, consisting of severing the free end of the web of the replacement roll on diagonal lines, thereby forming points adjacent the ends of the said replacement roll, applying adhesive to the said free end, holding the said points against the body of the roll by holding means rotatable with the roll, rotating the replacement roll at substantially the speed of the running web, pressing the running web against the replacement roll, and releasing the holding means from the points and from the roll when the running web engages the said points.

39. In a web roll changing mechanism, means for confining the free end of the web of a replacement web roll to the body portion thereof while the said roll is being rotated, and releasing the end when same is joined to a running web, said free end having adhesive material

thereon and being formed by severing the web on a diagonal line and forming a point adjacent an end of the web roll, and a holding device supported independently of the roll and adapted to hold the said point in engagement with the body of the roll, and to release the said point when the running web is pressed thereagainst.

40. In a web roll changing mechanism, means for confining the free end of the web of a replacement web roll to the body portion thereof while the said roll is being rotated, and releasing the end when same is joined to a running web, said free end having adhesive material thereon and being formed by severing the web on diagonal lines and forming points adjacent the ends of the web roll, and holding devices supported independently of the roll and adapted to hold the said points in engagement with the body of the roll, and to release the said points when the running web is pressed thereagainst.

41. In a web roll replenishing mechanism, means for holding the free web end of a web roll against the body portion thereof, including reinforcing means secured along the free end of said web, whereby the web end is prevented from tearing when the roll is rotated preliminary to making a web join.

JOHN R. TOMLIN.
ARVID LUNDQUIST. 30
